JOHN J. LYTH, OF VALLEYFIELD, QUEBEC, CANADA.

CLOTH-PILEING MACHINE.

1,321,834.

Specification of Letters Patent. Patented Nov. 18, 1919.

Application filed August 29, 1918. Serial No. 251,951.

To all whom it may concern:

Be it known that I, JOHN J. LYTH, a subject of the King of Great Britain, and resident of the city of Valleyfield, in the Province of Quebec and Dominion of Canada, have invented certain new and useful Improvements in Cloth-Piling Machines, of which the following is a full, clear, and exact description.

10 This invention relates to improvements in automatically operating machines for piling cloth in bleachery bins or in square open-top keirs, and the object of the invention is to provide a machine of simple, durable and 15 inexpensive construction, which will pile the cloth quickly and uniformly in the bins.

A further object is to provide a machine which will deal with cloth in either rope form or open width.

20 A still further object is to provide a machine which may be either individually motor driven or belt driven from a counter shaft.

Another object is to provide a machine 25 which is adjustable in its operation, so that while the range of operation may be over a number of bins, the machine may be adjusted to work over any one of them.

Still another object is to provide a machine 30 which will operate at high speed.

An additional object is to provide a machine which will lay the cloth smoothly, so that it may be removed from the bin without snarling.

35 For the most part, cloth is distributed in bleachery bins or the like by hand. The cloth is delivered usually in rope form in the center of the bin and an operator standing in the bin directs the cloth by means of

40 a pole to different parts of the bin, so that uniform distribution is effected and the rope of cloth is laid smoothly and without snarls.

In practice, the cloth is not laid with anything approaching the uniformity desired, 45 with the result that the density of the cloth in the bin varies greatly and the full capacity of the bin is not utilized. It frequently happens that the operators permit the incoming cloth to accumulate in the center of the bin

50 without distributing same and, in subsequently distributing this accumulation, they lay the cloth in such a way that it snarls on removal from the bin. The cloth coming to the bins is usually wet and therefore heavy

55 and difficult to handle. Machines have been devised for laying cloth in bins but are un-

satisfactory from a commercial point of view, owing principally to their slowness of operation and high cost.

The machine according to this invention 60 is of inexpensive and durable construction and will operate automatically up to any speed at which it is possible to supply it with cloth. Owing to the automatic operation, the machine distributes the cloth uniformly 65 and with absolute precision in the bin, so that uniform density, freedom from snarls and the utilization of the entire bin capacity result.

The device consists briefly of a pair of 70 parallel tracks of any desired length, upon which a carriage is mounted. This carriage carries a constantly rotating wheel, to which the cloth is delivered through a guiding eye moving transversely of the carriage. The 75 cloth passes over the roll and drops into the bin. The guiding eye is in reality a second and smaller carriage, which travels on tracks mounted on the carriage at right angles to the carriage tracks. The guiding eye is 80 operated back and forth by a right and left hand screw. The force which drives the carriage is communicated to the reel and to the screw, so that the two operate simultaneously. The carriage is provided with a 85 reversing drive controlled by adjustable stops, which may be set at any point in the carriage's travel, so that the carriage will travel back and forth the full length of its tracks or any part thereof defined by the 90 positioning of the stops.

In the drawings which illustrate the invention:—

Figure 1 is a side elevation of the device showing the driving end of the carriage. 95

Fig. 2 is an elevation showing the opposite side of the device.

Fig. 3 is a plan view.

Fig. 4 is an enlarged plan view of the driving end of the carriage, showing the 100 automatically reversing drive.

Fig. 5 is a cross sectional view of the carriage showing the mounting of the guiding eye.

Fig. 6 is a side elevation of the machine 105 showing the application of a motor drive thereto.

Fig. 7 is a diagram illustrating the operation of the machine.

Referring more particularly to the drawings, 110 11 designates the ceiling of a mill or framework over a bin, upon which the

machine is mounted, and 12 designate hangers depending from the ceiling or framework at the ends of a bin or row of bins and carrying the parallel carriage tracks 13, which are preferably steel beams of channel or I-section. The invention has been illustrated in Figs. 1, 2 and 3 as arranged for belt drive, so that this invention will first be described in detail and subsequently the differences incident to motor drive indicated. The hangers 12 project below the tracks 13 and carry a trough 14 to catch any droppings from the drive chain hereafter described. The ends of the hangers are connected by steady beams 15 at right angles to the tracks 13. Below the tracks 13, the hangers are provided with bearings 16, in which shafts 17 are journaled transversely of the tracks 13 and one at each end of the machine. One of these shafts is provided with a driving pulley 18 and each of the shafts is provided at one end with a sprocket 19. These sprockets are connected by an endless chain 20.

The carriage comprises a suitable framework 21 having running wheels 22 and 22^a at the four corners thereof, which travel upon the track beams 13. A large slatted drum 23 extending the full width of the carriage is journaled in the lower part thereof and has fixed thereto at one end a sprocket wheel 24, over which the endless chain 20 travels. The chain 20 is held in mesh with a considerable part of the circumference of the wheel 24 by a pair of idler pulleys 25, which may be adjusted to regulate the tension of the chain 20. The running wheels 22 may be connected to the carriage by individual studs, while the running wheels 22^a are for convenience mounted on the shaft 26, which extends the full width of the carriage and has fixed adjacent each end thereof a sprocket wheel 27. A chain 28 is mounted at each side of the device between the hangers 12 by means of adjustable hooks 29. These chains pass over the sprockets 27 and are held in mesh with a large portion of the sprocket circumference by idler pulleys 30, mounted in pairs on arms 31 pivoted on the shaft 26 and held against oscillation by a link 32 connected to the carriage frame.

At the opposite end of the drum from the sprocket 24, a sprocket 33 is fixed. This sprocket drives a bevel pinion 34 by suitable chain gearing 35. The bevel pinion operates between and drives two bevel gears 36, so that these gears obviously rotate in opposite directions. The gears 36 are both freely revoluble on a shaft 37 journaled in the carriage frame and carrying a relatively irrevoluble but slidable clutch member 38, between the gears 36, adapted to interlock with either of the gears. The shaft 37 also carries a worm 39 in mesh with a worm wheel 40 fixedly mounted on the shaft 26.

A fixed rod 41 is secured between the steady beams 15 above the shaft 37. This rod carries a pair of adjustable resilient stops, each of which comprises a collar 42 having means 43 for clamping it to the rod 41 at any point; a collar 44 sliding on the rod between the collar 42 and the carriage; and a helical spring 45 surrounding the rod and connecting the collars 42 and 44.

The clutch 38 is provided with a throwing lever 46, which projects upwardly into the line of the stop collars 44.

Below the tracks 13, the carriage supports a pair of parallel tracks 47 at right angles to the tracks 13. These tracks 47 are preferably steel beams of channel or I-section arranged back to back. A continuous right and left hand worm 48 is journaled in the carriage frame and extends parallel with and between the tracks 47. This worm carries a nut 49 which, in order to relieve the worm of all load, is provided with running wheels 50 traveling on both top and bottom of the tracks 47. The nut is further provided with running wheels 51 which engage adjacent faces of the tracks. The arrangement of these wheels and their distance apart is such that the nut cannot move up or down or rotate or jib, but can move with a minimum of friction in the axial direction of the worm. The nut carries a depending arm 52, which inclines toward the drum and is provided with a large eye 53 suitably rounded on its edges. One end of the worm is provided with a pinion 54 connected by a chain 55 with a sprocket 56 fixed to the drum.

In Fig. 6, an individual motor drive is shown and the arrangement differs from that previously described solely in the elimination of the parts 14, 15, 16, 17, 18, 19 and 25, and the substitution therefor of a motor 57 mounted at one end of the carriage frame and connected by suitable chain gearing 58 with the drive sprocket 24 of the drum. This motor is supplied with current through a flexible cable preferably depending from the ceiling. The motor may be mounted in any other location found desirable and suitably connected with the parts of the machine.

The operation of the device is extremely simple. The drum is revolved either by the motor 57 or by the continuously operating chain 20 and this revolution is transmitted through the chain gearing 35 to the bevel pinion 34, which drives the gears 36 in opposite directions. The clutch 38 being in mesh with one of the gears, the shaft 37 revolves the worm and worm wheel, so that the shaft 26 and sprockets 27 are revolved. These sprockets 27 are in mesh with the chains 28 which serve as racks. The result is that the carriage draws itself along these chains in one direction, the weight being

supported by the tracks 13. Simultaneously with the carriage movement, the drum revolution is transmitted to the right and left worm 48, which is revolved and thereby moves the nut 51 and eye 53 back and forth across the carriage. The gearing ratios are such that the nut travels many times back and forth while the carriage is traveling a given distance on the tracks 13. When the carriage approaches the limit of its travel, the clutch throwing lever 46 engages a stop collar 44 and slides it along the rod 41 with the carriage, thus compressing the spring 45. This compression of the spring is rendered possible by the resistance of the clutch to being thrown out, owing to the considerable power which it is transmitting. When the spring reaches a predetermined compression, it overcomes this resistance in the clutch and the clutch is thrown out, thus stopping the carriage. The spring compressing force due to the movement of the carriage being now removed and the clutch being free of the gears 36, the spring 45 expands and throws the clutch into engagement with the other gear 36. As the gears 36 are driven in opposite directions, it is obvious that the direction of revolution of the shaft 37 and therefore the direction of revolution of the sprockets 25 will be reversed, so that the carriage will commence to move in the reverse direction. The carriage, although very large and heavy, travels at the rate of only a few feet per minute, so that it has practically no momentum and stops instantly the driving power is cut off. Owing to the low gear which moves the carriage so slowly, the power applied is very great and the carriage will commence moving immediately the power is again applied. The no-power periods are theoretically and may be in practice only the instant of time required for the liberated spring 45 to expand and the clutch to engage, so that for all practical purposes the carriage may not be stationary any longer at the end of its travel than a high speed reciprocating object would be. This feature and its control are important, as it insures maintenance of proper relation between the carriage movement and position and the eye movement and position. By allowing a certain time lag at each reversal of the carriage, the relation of the carriage and eye is altered, so that the initial path of the eye will not be exactly retraced for a considerable time.

The cloth is fed into the eye in an approximately horizontal direction and is passed to the drum, its position on the drum being determined by the position of the eye. The heavy rope of cloth meshes to a certain extent with the slats of the drum, so that the drum pulls on the rope and draws it through the eye and then allows it to drop into that part of the bin determined by the positions

of the eye and carriage. The drum revolves always in the same direction, that is, away from the eye, regardless of the direction of carriage movement, and therefore always has the same effect on the rope of cloth.

The relation between carriage movement and eye movement causes the carriage to travel on an extended scale such a path as is shown in the diagram, Fig. 7. According to this diagram, which is theoretical, the carriage makes three trips before the eye commences to retrace its path. In practice, the machine may be adjusted to produce exactly this result or to increase or decrease the number of carriage movements before the eye commences to retrace its path. Very fine adjustments of the gearing, which would be necessary to produce such a result with absolute accuracy, may be dispensed with by permitting a slight slackness of the various chains, so that the time lag or dwell of the carriage at each reversal of its movement will enable the eye to enter into an altered relation. In this way, the desired result may be produced with great ease and without change of gearing.

It will also be noted that the eye and drum are below the mechanism, so that any drip of water or bleaching solution from the cloth will fall directly into the keir or bin without touching any of the moving parts and therefore without washing oil or dirt into the bin.

When it is desired to lay cloth in open width instead of in rope form, the cloth is passed under the roll 59 instead of through the eye and then over the drum. The eye being now out of use may be stopped by disconnecting its driving mechanism or may be allowed to run idle. By increasing the speed of the carriage, the cloth may be laid back and forth flatwise in the bin.

By arranging the bins in rows and placing the tracks 13 above the row and then adjusting the stops, the carriage may be made to travel back and forth over any one bin or over any part of one bin. When it is desired to move the carriage from one bin to the next, it is merely necessary to move the stop ahead of the carriage to the desired new stopping point and the carriage will follow until it reaches the stop. The other stop can then be moved up after the carriage to set the limit of retreat. During this change from bin to bin, the run of cloth through the machine need not necessarily be stopped, although in practice the capacity of the bin is known and the length of rope regulated accordingly, so that it will not be necessary to go into another bin. It is obvious that if the worm 48 is divided into two or more parts merely by providing connection between the right and left hand threads, two or more nuts may be used, so that two or more ropes of cloth may be piled simulta-

neously. This enables a machine large enough to straddle several rows of bins to pile cloth simultaneously in all the rows or, if operating over a single bin, to pile 5 several ropes of cloth into the one bin simultaneously, thus filling the bin with great rapidity.

While the invention has been shown as applied to overhead tracks, for the reason 10 that this will be the most usual installation, it is obvious that in mills where the mouths of the bins are at or near a floor level, the tracks 13 may take the form of rails on the floor. In other respects, the apparatus will 15 be exactly the same.

Having thus described my invention, what I claim is:—

1. In a device of the class described, a pair of parallel tracks, a carriage on said 20 tracks, transverse tracks mounted on the carriage, a drum revoluble in the carriage, a piling eye slidable on said transverse tracks, means for rotating the drum and for simultaneously and automatically reciprocating the piling eye on the transverse tracks and carriage moving means driven by said drum.

2. A device according to claim 1, in which the drum rotating and carriage moving 30 means comprise a sprocket fixed to the drum and an endless driven chain passing over said sprocket and delivering power thereto for the movement of the carriage and piling eye.

3. In a device of the class described, a pair of tracks, a carriage thereon, a cloth 40 piling means mounted in the carriage including a revoluble cloth feeding drum and a piling eye movable transversely of the direction of the carriage travel, means for driving said piling eye from the drum, a reversible driving mechanism for the carriage, means for automatically reversing the carriage driving mechanism and means for 45 automatically reversing the driving means of the piling eye a plurality of times during a single carriage movement.

4. In a device of the class described a reciprocatable carriage, a reciprocatable piling eye, a cloth feeding means in the carriage, a single drive for said cloth feeding means, carriage and eye connected to the feeding means to operate the same continuously in one direction, a reversible drive for 55 the carriage and a self-reversing drive for the piling eye both driven from said cloth feeding means.

5. In a device of the class described, a reciprocatable carriage, a cloth feeding 60 means therein, a drive for said feeding means, a shifting gear for said carriage, a carriage drive gear operatively connected with the cloth feeding means, and a reversing gear between the carriage driving and 65 carriage shifting gears.

6. In a device of the class described, a framework including a pair of tracks, a carriage mounted thereon, a driven shaft in said carriage, a carriage driving gear operatively connected with said shaft, a shifting gear mounted on the carriage, an adjustably tensioned chain mounted in the framework passing over said shifting gear, reversible gear connection between the carriage driving and carriage shifting gears, a 75 cloth feeding drum mounted on said shaft and a cloth guiding eye movable transversely of said drum and operatively connected with said shaft.

7. In a device of the class described, a 80 carriage, a driven shaft therein, a piling eye, a right and left hand screw driving said piling eye, and operative connection between the screw and driven shaft.

8. In a device of the class described, a 85 carriage, a driven shaft therein, tracks on said carriage, a nut slidable in said tracks and held by the tracks against revolution, a continuous right and left hand screw passing through said nut, operative driving 90 connection between the shaft and screw, and a piling eye carried by the nut.

9. In combination with a device according to claim 6, tracks on said carriage, a nut slidable in said tracks held by the tracks against revolution and carrying the guiding eye, a continuous right and left hand screw 95 passing through said nut and driving connection between said shaft and the screw.

10. In combination with a device according to claim 9, a gear on the drum shaft and a continuously moving endless chain passing over said gear.

11. In combination with a device according to claim 6, adjustable stops adapted to 105 operate the reversing gear.

12. In a device of the class described, a framework including a pair of tracks, a carriage mounted on said tracks including a piling device and a driving gear, an endless driven chain mounted on the framework and meshing with the driving gear of the carriage, a chain tensioned in the framework, a sprocket wheel mounted in the carriage in mesh with said tensioned chain and operative connection between the driving gear and the sprocket, whereby the carriage will shift itself along said tracks and take power from said endless chain during its travel.

13. In combination with a device according to claim 12, a reversing gear operatively connected between the driving gear, a sprocket wheel, and means automatically actuated by the carriage movement at predetermined points for operating said reversing gear.

14. In combination with a device according to claim 13, a cloth feeding roll mounted in the carriage, a piling eye movable trans-

versely of the line of carriage movement, means for reciprocating said piling eye, and driving connection between the feeding device and the driving gear and between the 5 piling eye reciprocating means and the driving gear.

15. In a device of the class described, a framework, a carriage reciprocatable thereon, a piling eye reciprocatably mounted on 10 the carriage and movable transversely of the line of carriage movement, and driving means reciprocating said carriage and piling eye, said means being arranged to reciprocate the piling eye more frequently than the 15 carriage per unit of time.

16. In a device of the class described, a cloth feeding drum, and means driven by the drum and movable transversely of the drum determining the position of the cloth 20 on the drum.

17. In a device of the class described, a cloth guiding eye, and a bodily moving feeding drum arranged to draw cloth through the eye and feed the same into a 25 receptacle, and means for moving the eye at considerably greater speed than the drum and transversely of the drum to determine the position of the cloth prior to feeding.

18. In combination with a device according to claim 17, a carriage supporting the cloth feeding and guiding means, and means 30

driven by the drum for reciprocating said carriage.

19. In a device of the class described, a carriage, a cloth feeding means and a cloth 35 guiding means thereon, means for moving the feeding means always in a positive direction, and means driven by the feeding means for moving the carriage and the cloth guiding means in positive and reverse directions in different planes. 40

20. In a device of the class described, a reciprocatable carriage including a cloth feeding drum driven constantly in one direction, a sprocket and a reversible driving 45 connection between the drum and sprocket, a fixed tensioned chain in mesh with said sprocket along which the sprocket draws the carriage, means for reversing the sprocket drive, a cloth guiding eye moving 50 transversely of said drum and means for regulating the dwell of the carriage at each reversal of its movement to regulate the positions of the drum and eye relative to a fixed point. 55

21. A device according to claim 20, in which the means for regulating the length of dwell comprises means for regulating the tension of the chain.

In witness whereof, I have hereunto set 60 my hand.

JOHN J. LYTH.
